CARRIER FREQUENCY AMPLIFIER

Heinz Hannemann and Ewald Oberländer, Berlin, Germany; vested in the Alien Property Custodian

Application December 13, 1940, Serial No. 370,048
In Germany December 12, 1939

5 Claims. (Cl. 179—171)

In carrier frequency telephone systems it is in several respects important to control the amplification effected by carrier frequency repeaters. In many cases an automatic control is desirable in order to stabilize the telephonic connections. In the case of uni-directional transmission systems, such as wired radio broadcasting systems, a constant transmission level is particularly desirable on account of the modulation and especially with a view to avoiding over-modulation of the subsequent repeaters and transmitters. The transmission level considerably varies where open lines are employed and in this case depends on weather and season conditions. With cables the level undergoes variations which are mainly due to season conditions and are comparatively small, which however in the case of transmission systems provided with many repeaters are nevertheless such that an automatic regulation should be provided. In high frequency transmission systems of the kind in which the carrier frequency is suppressed it is customary to control the transmission level with the aid of a separate so-called guide frequency. In carrier frequency systems operating with carrier transmission the carrier itself may be used for indicating level variations.

The known systems for indicating and controlling the transmission level act to rectify the guide frequency or the carrier frequency, as the case may be, by means of an additional device and they utilize the variable intensity of the resultant current for indicating a level increase or decrease with the aid of maximum or minimum relays, respectively, so-called marginal relays which are similar in structure to contact ammeters and voltmeters. This method, however, is insufficient inasmuch as these relays, having to respond or to release at predetermined current intensities, are sensitively adjusted and yet not reliable in operation. Besides they are sensitive to mechanical disturbances, such as shocks.

The present invention has for its object to provide means whereby an increase or decrease of the transmission level is indicated by the rectified current having positive direction in the event of a level increase and negative direction in the event of a level decrease, or vice versa. No continuous current is effective whenever the level agrees with the desired value. This principle also entails that the continuous current, caused by the level not agreeing with that value, even with small level variations becomes intense enough to insure a safe response of the respective signalling relay.

According to the invention this object is secured with the aid of a direct current bridge connection that comprises four resistances, one of these resistances or a number thereof being capable of varying under the influence of the carrier frequency.

In the drawing, Fig. 1 is a diagram illustrating the fundamental idea of the invention. Fig. 2 is a diagram showing one embodiment of the invention, this embodiment being based on the arrangement represented in Fig. 1. Fig. 3 is a graph referred to in explaining the operation of the system illustrated in Fig. 2. Fig. 4 is a diagram that shows a modification of the device represented in Fig. 2.

The bridge connection shown in Fig. 1 comprises four resistances R_1 , R_2 , R_3 , R_x and indicating devices which constitute the middle of the bridge and comprise direct current relays V , W arranged to respond to currents of definite direction, the direction in the case of each relay being opposite to that of the other relay. Resistance R_x is arranged to vary under the influence of the carrier frequency and in its resistivity depends upon the amplitudes. This resistance may be constituted by a vacuum tube D , Fig. 2, whose working point is so adjusted that the internal resistance of such tube shall balance the bridge whenever the measured level agrees with the desired level. In addition, variable resistances having an ascending or a descending resistance characteristic may be included in the bridge, namely, resistances which under the influence of the variation of R_x act to vary their own resistance under the influence of the variation of R_x . With the vacuum tube D employed as resistance R_x the working point of this tube is displaced by the carrier frequency rectified by the tube. The displacement is such that the internal resistance of the tube is decreased if, for instance, the level rises beyond the desired level, whereas it is increased whenever the level becomes less than the desired value, or vice versa. This behaviour means that with a change of the internal resistance R_x of the tube the bridge balance is affected in such a manner that on increase of resistance R_x a bridge current flows from B to A , Fig. 1, while decrease of resistance R_x causes a bridge current to flow from A to B . Consequently, relay W responds on resistance R_x increasing over the desired value, while relay V responds on the resistance R_x decreasing.

In order further to increase the variation of the internal resistance as regards the action on the relays V , W the arriving carrier amplitude is

rectified in an additional path and is then used to change the grid bias of the tube in a manner to increase the action on these relays. For this purpose, part of the carrier alternating voltage in the anode circuit is altered by a rectifier GI, Fig. 2, in a manner to counteract the grid potential, whereas in the case of a different use of the described arrangement it is altered to aid the grid potential.

The interrelation between the control direct current and the oncoming carrier amplitude is in Fig. 3 illustrated as test reading.

A further feature of the invention is that the means for regulating the amplification is not arranged in advance of the control repeater but is included therein, being disposed in the anti-coupling path, for instance.

Fig. 4 illustrates an anti-coupling for the tube D, which by way of example is shown to be joined to a resistance R_g and a condenser C_g in order to cause the internal resistance to vary uniformly within the available working range of the tube whenever the working point is displaced in accordance with a higher or lower potential.

What is claimed is:

1. Automatic level control means for carrier frequency amplifiers, comprising a direct current bridge connection including four resistances at least one thereof being variable when affected by carrier frequency, means affected by carrier frequency to alter the variation of said one resistance, and direction-responsive direct current relays connecting the center points of said bridge.

2. Automatic level control means for carrier frequency amplifiers, comprising a direct current bridge connection including four resistances, a vacuum tube constituting one of said resistances whereby said one resistance is variable when

affected by carrier frequency, means affected by carrier frequency to alter the variation of resistance of said tube and direction-responsive direct current relays connecting the center points of said bridge.

3. Automatic level control means for carrier frequency amplifiers, comprising a direct current bridge connection including a plurality of resistances, a vacuum tube constituting one of said resistances whereby said one resistance is variable when affected by said carrier frequency, said tube having a grid, means to bias said grid, a rectifier to alter the carrier voltage in the anode circuit of said tube to alter the bias of said grid, and direction-responsive direct current relays connecting the center points of said bridge.

4. Automatic level control means for carrier frequency amplifiers, comprising means, including a vacuum tube having a grid, to rectify incoming carrier currents, a direct current bridge connection including a plurality of resistances one thereof being said vacuum tube, means to bias said grid, means to alter the bias of said grid and direction-responsive direct current relays connecting the center points of said bridge.

5. Automatic level control means for carrier frequency amplifiers, comprising a direct current bridge connection including a plurality of resistances, one thereof being a vacuum tube having a grid, means to bias said grid, rectifying means to alter the bias of said grid, means to cause the internal resistance of the tube to vary uniformly within the available working range of the tube whenever the working point is displaced, and direction-responsive direct current relays connecting the center points of said bridge.
